UNITED STATES PATENT OFFICE.

DANIEL HOGAN, OF NEW YORK, N. Y., ASSIGNOR TO THE MEINECKE & COMPANY, OF SAME PLACE.

DESIGN FOR A DOUCHE-PAN.

SPECIFICATION forming part of Design No. 33,049, dated August 7, 1900.

Application filed July 7, 1900. Serial No. 22,883. Term of patent 14 years.

To all whom it may concern:

Be it known that I, DANIEL HOGAN, a citizen of the United States, residing at New York, borough of Manhattan, county and 5 State of New York, have invented and produced a new and original Design for a Douche-Pan, of which the following is a specification.

This design consists in a douche-pan having the front upper portion formed with a central 10 concave part and convex lateral parts and the sides gradually rising toward the rear, so as to form hump or elevated portions.

The design is illustrated in the annexed drawings, in which—

15 Figure 1 is a plan view of the pan. Fig. 2 is a transverse sectional view of the pan. Fig. 3 is a sectional side elevation of the pan. Fig. 4 is a perspective view of the pan.

The douche-pan is shown with the front upper portion formed with a central concave 20 part *e* and lateral convex parts *e'*. The sides of the pan gradually rise toward the rear, so as to form humps or elevated portions *e''*.

The design gives a striking and characteristic appearance.

What I claim as new, and desire to secure by Letters Patent, is—

The design for a douche-pan as herein shown and described.

In testimony whereof I have hereunto set 30 my hand in the presence of two subscribing witnesses.

DANIEL HOGAN.
